UNITED STATES PATENT OFFICE.

PIERCE J. STRIMPLE, OF SEKITAN, OHIO.

FOLDING CAR-STEP.

1,079,452.

Specification of Letters Patent. Patented Nov. 25, 1913.

Application filed August 4, 1913. Serial No. 782,983.

To all whom it may concern:

Be it known that I, PIERCE J. STRIMPLE, a citizen of the United States, residing at Sekitan, in the county of Hamilton, State of Ohio, have invented certain new and useful Improvements in Folding Car-Steps; and I do hereby declare the following to be a full, clear, and exact description of the invention, such as will enable others skilled in the art to which it appertains to make and use the same.

This invention relates to new and useful improvements in folding car steps.

The object of the invention resides in the provision of a bottom step for the platform of vehicles and particularly steam railroad vehicles and to means for raising and lowering the step. To this end the invention contemplates utilizing compressed air from the train line to actuate the step.

A further object of the invention resides in the provision of such a device which is easily operated and which is fully efficient under varying conditions of service.

The invention still further contemplates the provision of such a device possessing maximum simplicity of structure so that it is durable in use and may be manufactured at a comparative low cost.

With these and other objects in view, the invention resides in the novel combination, formation and arrangement of parts to be more fully hereinafter described and illustrated in the accompanying drawings and particularly pointed out in the claims hereto appended.

Reference is had to the accompanying drawings wherein similar characters of reference designate corresponding parts throughout the several views, and in which:

Figure 1 is a side elevational view of the platform steps with the improved folding step and means for actuating the same, Fig. 2 is a top plan view of what is shown in Fig. 1, Fig. 3 is a vertical longitudinal sectional view on the line 3-3 of Fig. 2, Fig. 4 is a longitudinal sectional view taken through the valve, Fig. 5 is a transverse sectional view therethrough on the line 5-5 of Fig. 4, and Fig. 6 is a detail sectional view of the bracket for holding the step engaging rod.

Referring now more particularly to the drawings, wherein is shown the preferred embodiment of the invention, 5 designates

the platform of a car and 6 the sideboards or stringers with which are associated the usual tread portions 7 and risers 8 forming steps for entering or leaving the car. The extension step portion comprises a riser 9, 60 hinged as at 10 to the outer edge of the lower tread portion and a tread portion 11 is hinged as at 12 to the bottom of the riser 9 so that the said tread cannot swing to an angle of more than 90 degrees. When this 65 extension step is folded, it is observed that the same is disposed under the lowermost stationary tread and thus forms no obstruction or inconvenience when it is not in use.

For moving the step to folded position, a 70 bar 13 is pivoted at 14 to each side of the tread portion 11 and is slidably mounted in brackets 15 disposed on the outer faces of the side portions 6 of the stationary step. Each of these brackets comprises a base 75 plate 16 and a second plate 17 having its end portions 18 inwardly offset, belts 19 being passed through the end portions 18 and through the base plate to secure the brackets in position. Rollers 20 are provided having pintles 21 journaled in the plates and the bar 13 extends between these rollers to reduce the friction incident to its movement. Means are provided for actuating this bar by means of compressed air from the train 85 line to fold or unfold the step. To accomplish this, a cylinder 22 is positioned on the outer face of each side portion 6 and held by the straps 23. Slidably in each cylinder is a piston 24 from which extends outwardly of the cylinder a stem 25 having its free end threaded and held in a bore formed in an arm 26 and bolted to the operating rod 13, by means of the nuts 27 disposed on each side of the arm. The valve mechanism 90 for supplying air to either end of these cylinders to fold or unfold the steps comprises a valve casing 28 disposed under the platform. A feed pipe 29 leads from the train line to the top central portion of the casing. An outlet pipe 30 leads from one end of the casing to a pipe 31 which connects the upper ends of the cylinders and a pipe 32 leads from the other end of the casing to a pipe 33 connecting the other ends of the cylinders. An exhaust pipe leads from the central portion of the cylinder, said pipe communicating with the casing on a straight line between the communicating points of the pipes 30 and 32. The 100

105

110

- valve head 34 is slidable in the casing and has its top portion cutaway throughout its length and has the intermediate portion of its bottom cutaway to form the passage 35.
- 6 When the casing is at one limit of movement the air passes from the feed pipe through the top portion of the casing to the pipe 30 and from thence to the pipe 31 which delivers it to the upper ends of the
- 10 piston cylinders causing the pistons to move downwardly and thus move the bars 13 and extend the steps, the air from the lower ends of the piston cylinders passing through the pipe 33 to the pipe 32 and from thence through the passage 35 into the exhaust pipe. When it is desired to raise or fold the step the valve is shifted and the operation above-described is reversed.
- For actuating the valve head, a stem 36
- 20 extends outwardly therefrom and is pivotally connected to an arm 37 fixed to a shaft 38 which is suspended by the hangers 39 from the bottom of the platform. This shaft is rocked by a lever 40 fixed to and upstanding therefrom, a rack bar 41 being secured to the platform and a grip operated pawl 42 being carried by the lever whereby the shaft is held at either desired limit of movement.
- 25 It will be understood that various minor changes and modifications within the scope of the appended claims may be made without departing in any manner from the spirit of the invention, as for instance, other suitable means for actuating the valve may be used, if desired.

What is claimed is:

1. An extension car step comprising the combination with the platform steps, of a tread pivotally secured to the riser, brackets 40 on the sides of the car steps, bars slidable in the brackets and pivotally connected to the outer portion of the tread, cylinders disposed on the sides of the steps, pistons slidable in the cylinders and having stems 45 extending therefrom, lateral arms on the bars connected to the stems and means for introducing compressed liquid into either end of each cylinder.
2. An extension car step comprising the combination with platform steps, of a hinged tread portion, cylinders on the sides of the steps, pistons slidable in the cylinders and connected to the tread, a pipe connecting the outer ends of the cylinders, a pipe connecting the inner ends of the cylinders, a valve casing, pipes connecting adjacent ends of the valve casing and the first-mentioned pipes, an inlet port in the upper end of the casing, an outlet port, and a valve head 60 slidable in the casing and having its upper portion cutaway and being provided with a passage selectively connecting the outlet port and one of the pipes communicating with the first-mentioned pipes. 65

In testimony whereof, I affix my signature, in the presence of two witnesses.

PIERCIE J. STRIMPLE.
